ATTORNEY.

UNITED STATES PATENT OFFICE.

LEVI BERGER, OF PHILADELPHIA, PENNSYLVANIA, ASSIGNOR OF ONE-HALF TO WILLIAM H. BERGER, OF SAME PLACE.

DESIGN FOR BUCKET-EARS.

SPECIFICATION forming part of Design No. 12,304, dated June 14, 1881.

Application filed April 14, 1881. Term of patent 14 years.

To all whom it may concern:

Be it known that I, LEVI BERGER, a citizen of the United States, residing at Philadelphia, in the county of Philadelphia and State of Pennsylvania, have invented and produced a new and original Design for Bucket-Ears, of which the following is a specification, reference being had to the accompanying drawing, forming part thereof.

10 The figure is a view of the ornamented outer surface of the ear, being the only view necessary to fully illustrate my design.

15 Heretofore bucket-ears have been made with the portion known as the "flange" of smooth iron, with a plain surface and without ornament. The neck and eye portions, moreover, were formerly made plain without ornament.

20 The leading feature in my design consists in a raised ridge or broad line extending in certain directions over the outer surface of the ear, and the angular-cornered flange, as seen in the figure.

25 Referring to the figure, it will be seen that the margin of the flange extends to right and left of the neck or shaft in a straight line at right angles with the neck for a certain distance, then turns down at an angle of ninety degrees, (90°), forming a corner. These sides extend downward for some distance, then 30 make an oblique turn downward and inward toward the median line at an angle of about forty degrees, (40°), and extend onward about one-quarter the breadth of the flange, then make an oblique turn upward toward the me-

dian line, and the two sides meet at the center, 35 thereby forming two angular scallops on the lower edge of the flange and presenting seven (7) corners on the flange. About the eye is formed a raised ridge, which conforms to the curvature of the eye for a distance somewhat 40 greater than one-half the circumference of the eye at the upper part. From below the middle the ridges converge in a straight line toward the median line, where they unite, forming a straight line. This single ridge or line extends 45 in a straight line along the middle of the neck down to near the middle of the flange, where the ridge splits into two parts, one going to the right and the other to the left, and they continue in a curved line till they reach the 50 rivet-holes in the flange, where they make a single turn about these and encircle them.

I claim—

1. The design for a bucket-ear herein shown and described, the same consisting of a raised ridge or line surrounding the eye in a curved line, and extending in a straight line along the neck and spreading out on the flange in two lateral branches, the extremities of which encircle the rivet-holes. 55

2. The design for a bucket-ear herein shown and described, having a smooth seven-cornered flange with two angular scallops at the lower margin. 60

LEVI BERGER.
